UNITED STATES PATENT OFFICE

148,035

DESIGN FOR A LAWN SPRINKLER

Glenn S. Parker, Denver, Colo.

Application April 8, 1946, Serial No. 128,377

Term of patent 7 years

(Cl. D91—1)

To all whom it may concern:

Be it known that I, Glenn S. Parker, a citizen of the United States of America, residing at Denver, in the county of Denver and State of Colorado, have invented a new, original, and ornamental Design for a Lawn Sprinkler, of which the following is a specification, reference being had to the accompanying drawing, forming part thereof.

The drawing illustrates a perspective view of a lawn sprinkler showing my new design.

The opposite side of the sprinkler head, not shown, is substantially like the side shown.

I claim:

The ornamental design for a lawn sprinkler, as shown and described.

GLENN S. PARKER.
